H. C. GOOD SPEED, OF NEW YORK, N. Y.

Letters Patent No. 83,626, dated November 3, 1868.

IMPROVEMENT IN SASH-SUPPORTER

The Schedule referred to in these Letters Patent and making part of the same.

To all whom it may concern:

Be it known that I, H. C. GOOD SPEED, of New York, in the county of New York, and State of New York, have invented a new and improved Window-Frame and Sash-Balance; and I do hereby declare that the following is a full and exact description of the same, reference being had to the accompanying drawings, and to the letters of reference marked thereon.

This invention consists in an arrangement of cords, pulleys, and springs, hereafter more fully described, by which arrangement the sashes of a window may be steadied and balanced at any height which may be desired, without the use of weights and catches.

It is especially designed for the windows of houses, but may be equally well applied to cars or coaches, or any moving structure, as its operation is nowise interfered with by change of position or jarring of collision.

In order that those skilled in the art to which my invention appertains may construct the same, I will proceed to describe its construction and operation, reference being had to the drawings, and letters of reference written thereon, the same letters in the different figures marking different views of identical parts.

Figure 1 shows a front elevation of the sash, and frame which holds it, parts of the frame being broken away to disclose the arrangement of the pulleys and cords arranged thereon.

Figure 2 shows a more particular view of the construction and arrangement of the pulleys and their connected cords.

A is the sash, constructed in the ordinary manner.

B is the frame of the window, differing from the ordinary frame only in the open spaces for the location of the pulleys, and the passages which permit the free play of the cords.

In both the figures, *a a a* are sheaves or pulleys of the ordinary construction, and *b* a similar pulley, having two grooves on its periphery, instead of one, as in the others.

C are the cords, attached firmly to the upper and lower corners of the sash, at the outer edges of it, in such a manner as not to interfere with the easy passage of the sash in its frame; these cords passing around the pulleys, as shown in fig. 1, and being attached to a spring, *D*, in such a manner that the extreme elevation or depression of the sash will not bring the spring in contact with the pulleys, either above or below.

The spring is made preferably of coiled-steel wire, but may be of any permanently elastic material, and

is provided at its extremities with hooks or loops, for connection with the cords.

The operation of my invention is as follows:

The upper cord *C*, being carried through between the double and single sheaves, over the single and through the second groove of the double, is extended down and attached to the spring. The lower cord *C* is similarly arranged, except, for obvious reasons, the double pulley is omitted. The upper pulley may have its bearings in slots, so that when the pressure of the cord bears upon it, it will impinge against the lower or double pulley, and gripe the cord, in which case provision must be made for elevating the bearings, to relieve the gripe when the window is to be lowered. These slotted bearings, however, are not an essential modification, and might be well applied, perhaps, to car-windows, where the upper cord would necessarily be attached to the lower part of the sash, making the upper sheave accessible, and where there might be unusual jar.

The cords being arranged closely, as above described, it is evident that the sash will be securely balanced, and may be elevated, and will remain stationary at any point, without the aid of props, or catches, or weights, and may easily and readily be closed or changed, with only the application of the hand to the sash. It will be obvious that the sash is held, by this arrangement, securely in place at all times, and without danger of rattling. Another advantage gained is, that there are no unsightly catches fastened upon any part of the sash or frame. My device is cheaply and easily applied, and will not get out of repair, performing its functions until the materials of which it is composed actually wear out. The described device is shown only on one side of the sash, but may obviously be applied to both.

Having thus described my invention,

What I claim, and desire to secure by Letters Patent, is—

The construction and arrangement of the grooved single pulleys or sheaves *a a*, double sheave *b*, cords *C C*, and spring *D*, when applied to a window-sash and frame, substantially as described, and for the purpose set forth.

This specification signed and witnessed, this 18th day of March, 1868.

H. C. GOOD SPEED.
